UNITED STATES PATENT OFFICE.

WILLIAM M. THOMAS, OF CINCINNATI, OHIO.

POWDERED-COAL FEEDER.

Application filed March 24, 1926. Serial No. 96,978.

The object of my invention is to produce a simple, highly efficient and uniform feeding device for delivering powdered coal to a burner, furnace or other fuel consuming element.

One of the objects of my invention is to feed the powdered coal in less or greater volume, as needed by the consumer or fuel burning element.

10 Another feature of my invention enables me to feed the powdered coal of uniform density and quality, free from any extraneous material or matter, inasmuch as I screen all the coal before it is fed to the consuming 15 flame.

Another feature of the invention enables me to use the powdered coal with or without the mixture of air.

One of the salient features of my invention 20 consists in the employment of a set of conveyors and a brush element, generally in horizontal adjustment operating in connection with or without a source of air and in connection with a blower element for sucking out the powdered coal and blowing 25 it to a point where it is to be consumed.

Another feature consists in operating the conveyor and brush in a tube like element, the upper half of which is of a screen form, 30 through which the powdered coal is sifted and brushed off by the revolving brush element.

Other objects and features of the invention 35 will become apparent from reading the following specification and claims.

In the accompanying drawing forming part of this specification:

Fig. 1, is a view in elevation of one end 40 of my powdered coal delivering device or apparatus, partly in section and partly broken away,

Fig. 2, is a plan view of the same,

Fig. 3, is a longitudinal section of same, parts broken away and parts in elevation,

45 Fig. 4, is a sectional view taken on the line 4-4 of Fig. 3,

Fig. 5, is a sectional view, taken on the line 5-5 of Fig. 3,

50 Fig. 6, is a sectional view, taken on line 6-6, of Fig. 3, however being an enlarged view,

Fig. 7, is a longitudinal section of the coupling joint between the motor and the device itself,

55 Fig. 8, is an end view of the parts shown in Fig. 7, partly in section,

Fig. 9, is a sectional view, taken on the line 9-9 of Fig. 3, and

Fig. 10, is a view in elevation of the draft door, taken from line 10-10 of Fig. 3.

In carrying out my invention, I provide a body portion 1, supported on legs 2, and having an upper receptacle 3, in which the powdered coal or coal dust is contained. The body 1 and the receptacle 3 may be supported and connected together in any suitable or approved form.

The body part 1 is formed into a hopper having inclined surfaces 4. In the body part 1 provide conveyors 5, supported upon a shaft 6, said shaft being square and its ends fit into square hubs 7, of the conveyors 5. Said conveyors are of a screw shaped type but may be of any form.

One end of shaft 6 is mounted in a blower 8 and said blower is rigidly attached to the side 9 of the body part 1. This blower is of any of the ordinary styles and need not be here described, as same is well known in the art. An opening 10 is provided in the side 9, to allow the powdered coal or dust to be drawn therethrough by the blower 8, said blower drawing said powdered coal by suction.

At the opposite end of shaft 6, I provide 85 a motor 12, having a shaft 13 which is connected with shaft 6 by a coupling 14, which is held in position by a screw 15. The shaft 13 is provided with a nose 16 which engages with a nose 17 of shaft 6, (see Fig. 7). The 90 purpose of this coupling is to enable the operator to remove the motor without displacing any parts of the apparatus. It will be noticed that the shaft 6, at the end joint described, is mounted in a sleeve 18 having 95 a thrust collar 19, against which one of the conveyors 5 abuts, (see Fig. 3). The sleeve 18 forms an inner race for a ball bearing, having the outer race 20. This sleeve and bearing are mounted in a plate 21, which is 100 securely fastened to the side 22 of the body 1.

The side 22 has an opening 23 through which air is admitted, after said air has 105 suitably passed through openings 24 of the plate 21.

On the outer edge 26 of the plate 21 I mount shutter 25. The shutter regulates the amount of air admitted through the opening 23, by turning the shutter 25 either to or toward an open or to a closed position, by the knob 27; this shutter is provided with

holes 28 to coincide with the holes 24 in the plate 21.

Centrally located on shaft 6, between the conveyors 5, I provide a spiral brush 29, having a square hub 30; this brush is held between the conveyors 5, by an adjusting collar 31, which is held in position by a screw 32. This collar 31 and screw 32, hold the conveyors 5 and the brush in place at one end, and at the opposite or other end the collar 19 performs the same function.

The brush 29 and the conveyors 5 operate inside of a tube or cylinder, formed of a lower half 33, which is a half tube, and the upper portion or half tube 34, this upper half tube being smaller, and formed of a wire netting or screen mesh as shown in Fig. 4. The upper half is secured to the lower half at points 35, the upper half being thus supported, the lower half being supported on the bearings 36, (see Fig. 3). These two halves form a space or home in which the conveyors 5 and brush 29 operate, and are usually the entire length of the inside of the hopper and body portion 1 of the apparatus.

In carrying out my invention I further provide shutters 37; mounted in the guides 38, which in turn are secured to the sides 9 and 22 of body part 1. These shutters are operated by the segment gears 39 mounted at each end of the said shutters 37; these segment gears mesh with the gears 40, which are mounted on the shafts 41, which shafts are journaled at one end in the side plates 21 and at their opposite ends are journaled in the sides 9 of the body 1.

At the motor end of the shafts 41, I mount a knurled adjusting knob 42, which when turned revolves the gears 40, thereby causing the shutters 37 to be adjusted to allow more or less powdered coal to enter through the opening 43 formed by the said shutters.

On part 3 of the top, I provide an opening 44, through which opening I provide a wire screen by using a pouch or receptacle 45, which has a reinforcement ring 47 at its upper extremity, which ring is held in place by the ring 46 of part 3. A cover 48 is used to close and cover the opening 44 and the receptacle 45.

In order to keep the powdered coal from packing around the operating parts, I connect a deflector 51, to the sides 9 and 22 to allow freedom of action of the shutters 37 in the guides 38.

The device operates as follows; the powdered coal or coal dust is passed through the receptacle or strainer 45 and fills up the body 1. In order to allow varying amounts of this powdered coal dust to be used, the shutters 37 are adjusted as heretofore described; this allows the proper and desired amount of coal dust to pass through the opening 33 of the shutters 37, and then it is

passed through the wire screen or strainer 34, and it passes through and is brushed off of the screen by the edges of the brush 29, the motor 12 being in operation and revolving said brush and the conveyors 5, simultaneously; the conveyer 5 at the motor end of the apparatus drawing in the air to be mixed with the powdered coal and the conveyor 5, at the other end conveying the powdered coal to the blower 8, which now is creating a vacuum or suction drawing the coal dust into itself and emitting it with force out of opening 50 to the burner or fire at any point desired. By looking at Fig. 4 it will be seen that the brush is brushing up against the screen 34, sweeping and brushing off the powdered coal and at the bottom it is not so close to the lower half tube 33.

It will be seen and understood that the brush brushing and impinging against the screen 34 also keeps the powdered coal or coal dust in a state of agitation. When in operation a draft is present in the space 49 its entire extent.

While I show a preferred form of my invention, I may modify and change the same without departing from the spirit and principle of the invention and I claim any such modifications which fall within the scope of the appended claims.

What I claim as new and my invention, and desire to secure by Letters Patent is:

1. An apparatus for feeding pulverized fuel, comprising a hopper having aligned openings in its opposite walls, a tube in the hopper including a perforated segment and an imperforate segment, a conveyor rotatably mounted in the tube and including a brush for sweeping powdered fuel from the perforated portion of the tube, means for drawing air through said openings and said tube, and means in the hopper for regulating the fuel fed to the perforated portion of said tube.

2. In an apparatus for feeding powdered fuel, a hopper, a hollow perforated tube at the outlet of said hopper, a rotatable spiral conveyor in the tube provided with a brush contacting with the perforated portion of the tube for brushing fuel from the latter, and means for causing a draft of air through said tube for mixing the air with the fuel fed by the conveyor.

3. In an apparatus for feeding powdered fuel, a hopper, a hollow perforated tube at the outlet of said hopper, slidable shutters arranged in the hopper exteriorly of the tube, and adapted to move toward and away from each other, means for actuating said shutters, a rotatable spiral conveyor in the tube, and means for causing a draft of air through said tube for mixing the air with the fuel fed by the conveyor.

4. In an apparatus for feeding powdered fuel, a hopper, a hollow perforated tube at

the outlet of said hopper, curved shutters slidably mounted in the hopper and movable toward and away from each other for regulating the fuel fed to the perforated portion 5 of the tube, gearing for actuating said shutters, means for operating the gearing from the exterior of the hopper, a conveyor in the tube, and means for causing a draft of air through said tube for mixing the air with 10 the fuel fed by the conveyor.

5. In an apparatus for feeding powdered fuel, a hopper, a hollow perforated tube at the outlet end of said hopper, a rotatable shaft arranged in the tube, a spiral brush 15 and a spiral screw arranged on the shaft, and forming a conveyor, means for rigidly connecting the screw and brush to said shaft,

and means for causing a draft of air through the tube for mixing the air with the fuel fed by the conveyor.

6. In an apparatus for feeding powdered fuel, a hopper, a hollow perforated tube at the outlet of said hopper, a rotatable spiral conveyor in the tube, means for causing a draft of air through said tube for mixing 25 the air with the fuel fed by the conveyor, means for admitting air to one end of said tube, and means for regulating the admission of the air to that end of the tube.

In testimony whereof, I affix my signature 30 at Cincinnati, Ohio, this 16th day of March, 1926.

WILLIAM M. THOMAS.
